(57) **CLAIM**

The ornamental design for an electronic high-hat cymbal, as shown and described.

DESCRIPTION

FIG. 1 is a perspective, bottom view of an electronic high hat cymbal.

FIG. 2 is a side view of the electronic high hat cymbal.

FIG. 3 is a top view of the electronic high hat cymbal.

FIG. 4 is a side view opposite of the side view of FIG. 2, of the electronic high hat cymbal.

FIG. 5 is a bottom view of an electronic high-hat cymbal.

FIG. 6 is a further side view of the electronic high hat cymbal; and,

FIG. 7 is yet a further side view of the electronic high hat cymbal.

The broken lines in the drawings are shown for illustrative purposes only and form no part of the claimed design.
